WILLIAM A. COOK AND EVERETT P. STROUE, OF MARION, INDIANA, ASSIGNEES TO MARION MACHINE, FOUNDRY & SUPPLY COMPANY, OF MARION, INDIANA, A CORPORATION.

SOOT BLOWER.

Application filed April 7, 1924. Serial No. 704,773.

The object of this invention is to improve the operation of soot blowers by enabling the steam valve to be operated while the blow tube is at rest and to have the valve open and substantially in full blast position before, and during rotation of the blow tube and closed only after such rotation ceases.

The full nature of the invention will be understood from the accompanying drawings and the following description and claims:

In the drawings, Figure 1 is a vertical central section through the soot blower, parts being broken away and showing it in an intermediate position. Fig. 2 is an elevation of the rear side of the sprocket wheel and associated parts when the device is in a position intermediate the beginning and the end of the cycle of operation and corresponds to Fig. 1. Fig. 3 is similar to Fig. 2 with the parts therein shown in the position when the valve operating means ceases to rotate the blow tube. Fig. 4 is a sectional view of the steam valve mechanism when partially opened and when the sprocket wheel is in the position shown in Fig. 3. Fig. 5 is similar to Figs. 2 and 3 and shows the sprocket wheel at the beginning of the tube movement, the pin 51 being shown as having just passed under cam 50. Fig. 6 is the same as Fig. 4 showing the steam valve when open full.

In the drawings there is shown a wall box 10 adapted to be mounted in a steam boiler in rigid position and extending towards the flues, not shown, and having an outer head plate 11 to which the soot blower is mounted. Within and longitudinally of the wall box, the blow tube 12 is located, it having nozzles not shown for the exit of steam therefrom for directing the steam against the boiler tubes, as is well known in this art. The outer end of the tube 12 is screwed or otherwise secured in a tubular coupling 13 carrying a sleeve 14 rotatably mounted in the plate 11. The outer end of the coupling 13 is screwed or otherwise secured to a swivel tube 15 that extends to the outer end of the blow head mechanism. It is observed that the swivel tube 15, coupling 13 and blow tube 12 constitute one continuous rotatable tubular construction or conduit for the passage of steam to and through the blow tube.

The steam enters the swivel tube 15

through an annular series of ports 16 and through which steam passes from a goose-neck or steam pipe 17 which is supplied with steam through a pipe 18. The goose-neck is held in place by a bar 19 which is bolted by a bolt 20 to the plate 11. The gooseneck is formed of a lower pipe that is coupled by means of the bolts 21 with a valve chamber 22 having a port 23 adapted to be controlled by the steam valve 24 on a stem 25 mounted in a guide 26, so that said guide and stem are horizontal and the valve 24 operates horizontally. The steam passing the valve 24 enters an annular steam chamber 27 that surrounds the swivel tube 15 and the ports 16 therein, as shown. This steam chamber 27 is stationary and there are suitable packing joints between it and the swivel tube 15 so that the latter can rotate and the joints be steam tight.

The blow tube 12 is not continuously rotated and, therefore, the sprocket wheel 30 is not rigidly mounted thereon, but its hub 31 is rotatably mounted on the coupling 13. This sprocket wheel 30 is operated by a chain, not shown, which hangs down so as to be accessible to the workman, as is well known in this art. The sprocket wheel 30 has on its outer face an annular spur gear 32 held by bolts 33 and said spur gear meshes with a pinion 34 secured on the valve stem 25. The valve stem 25 is screw threaded in the guide 26 so that when the pinion 34 is rotated in one direction, the valve 24 will be moved so as to open and when rotated in reverse direction, said valve will be moved so as to close. The gearing may be such that the valve stem and pinion 34 will be given one revolution by a quarter turn of the sprocket wheel, which will remove the valve 24 laterally the distance of one thread on the stem 25, although the invention is not limited to the exact degree of the above-specified gearing and valve movement. When the sprocket wheel is moved in the direction of the arrow shown in Fig. 5, it will give the valve an opening movement and when moved in the opposite direction, see Fig. 3, it will give a closing movement.

The sprocket wheel rotates the blow tube 105 construction through the instrumentality of a pawl 40 secured on a pin 41 which is loosely pivoted in an ear or extension 42 from the hub 31 of the sprocket wheel, and a spring 43 tends to hold a flat tooth 44 of the

pawl in the rectangular notch 45 longitudinally cut in the periphery of the sleeve 14, which sleeve is secured on the coupling 13 and causes it and the tubes 12 and 15 to turn.

8 The stationary plate 11 has an annular undercut groove 46 in the outer face thereof concentric with the axis of the sprocket wheel 30, sleeve 14 and tubes 12, 13 and 15. Adjustably and rigidly mounted in that 10 groove is a headed nut 47 which pivotally supports and extends through a cam arm 48 curved concentric with the sleeve 14 and held against the latter by a spring 49. On the end of said arm 48 there is a forwardly-extending cam plate 50, shown by dotted lines in Fig. 1, and in side elevation in Fig. 2. This cam plate 50 projects forwardly into the path of pin 51 of the pawl 40, as seen in Fig. 1. Pin 51 may pass under 15 cam 50.

20 The operation of the device is as follows: Assume the parts to be in position as shown in Figs. 1 and 2, with the steam valve partially opened, and the pawl 40 in the notch 25 45 of the sleeve 14 of the coupling 13 of the blow tube. This may be called an intermediate or normal blowing position. When the sprocket wheel is turned in the direction of the arrow to the position shown in Fig. 30 3, the valve 24 will be further closed, as shown in Fig. 4. Then the projecting pin 51 on the free end of the pawl 40 rides up on the cam plate 50 to the position shown in Fig. 3, which lifts the pawl out of the 35 notch 45. The blow tube now remains stationary and steam thereafter is cut off by the complete closing of the valve 24 through further counter-clockwise rotation of the sprocket 30.

40 Reverse turning of the sprocket wheel in the direction of the arrow seen in Fig. 5, will first open the valve 24. Continued clockwise movement of the sprocket 30 permits the tooth 44 of the pawl 40 to seat in 45 the notch 45 and thus carry the tube 12 with said sprocket. Prior to the time the tooth 44 seats in the notch 45, the blow tube 12 is stationary and receiving the full steam blast and directing the same against the boiler tubes. The clockwise rotation of the sprocket 30 may be continued until the desired 50 degree of blow tube rotation, i. e., 320 degrees, has been made, whereupon the movement of the sprocket 30 is reversed.

55 It is thus seen that in operation of this soot blower, the steam valve will be opened before the blow tube begins to turn and this admits a charge of steam to the blow tube when it begins to turn at full pressure; that 60 the blow tube will be turned to the desired position to obtain the best action on the boiler tubes; that the blow tube when rotating is supplied with full steam pressure; and that the blow tube remains stationary 65 while the valve is closing.

One advantage of this blower over other blowers is that the valve is operable while the blow tube is at rest, and when it starts to turn the valve is appreciably open. Steam action is assured as soon as the tube 70 begins to turn and it is continuous while the blow tube is moving or when said tube is held stationary in an intermediate position.

The invention claimed is:

1. A soot blower including a rotary blow tube construction, means for supplying steam thereto, a steam valve for controlling said steam supply, a wheel loosely and rotatably mounted on the blow tube construction and adapted to operate the valve and 80 open and close the same and rotate the blow tube construction, and means for disengaging said wheel from the blow tube construction during a part of the cycle of the operation of the device. 85

2. A soot blower including a blow tube construction, means for supplying steam thereto, a steam valve for controlling said steam supply, a sprocket wheel loosely mounted on the blow tube construction, 90 means whereby rotation of said sprocket wheel operates the valve, a pawl connected with the sprocket wheel for engaging the blow tube construction and rotating it with said sprocket wheel, and stationary means 95 for disengaging said pawl from the blow tube construction whereby the sprocket may continue to rotate without rotating said tube construction.

3. A soot blower including a blow tube 100 construction, means for supplying steam thereto, a steam valve for controlling said steam supply, a sprocket wheel loosely mounted on the blow tube construction, means whereby rotation of said sprocket 105 wheel operates the valve, a pawl connected with the sprocket wheel for engaging the blow tube construction and rotating it with said sprocket wheel, stationary means for disengaging said pawl from the blow tube 110 construction whereby the sprocket may continue to rotate without rotating said tube construction, and means for mounting said pawl controlling means so that its position 115 can be adjusted for predetermining the initiation of rotation of the blow tube.

4. A soot blower including a rotatable blow tube construction, a steam supply pipe for supplying steam thereto, a steam valve for controlling said steam supply 120 which is provided with a threaded stem whereby when it is turned in one direction the valve will be opened and when turned in the opposite direction the valve will close, a pinion on said valve stem, a sprocket wheel 125 mounted on said blow tube construction and adapted to give the blow tube rotary movement, and a gear secured on the side of the sprocket wheel concentric therewith and meshing with said pinion, whereby the valve 130

will be given an opening movement during the rotation of the sprocket wheel in one direction and closing movement when the sprocket wheel is given a reverse movement.

5. A soot blower including a rotatable blow tube construction, a steam pipe for supplying steam thereto, a valve for controlling the steam supply which is mounted on a threaded valve stem, a pinion on said valve stem, a sprocket wheel loosely mounted on said blow tube construction, a gear secured on the side of said sprocket wheel concentric therewith for driving said pinion, and a releasable pawl connected with said sprocket wheel adapted to engage the blow tube construction and rotate it in either direction of rotation of the sprocket wheel.

6. A soot blower including a rotatable blow tube construction, a steam pipe for supplying steam thereto, a valve for controlling the steam supply which is mounted on a threaded valve stem, a pinion on said valve stem, a sprocket wheel loosely mounted on said blow tube construction, a gear on said sprocket wheel for driving said pinion, a pawl connected with said sprocket wheel adapted to engage the blow tube construction and rotate it in either direction of rotation of the sprocket wheel, and a cam adapted to disengage said pawl at a certain period of the rotary movement of the sprocket wheel.

7. A soot blower including a rotatable blow tube construction, a steam pipe for supplying steam thereto, a valve for controlling the steam supply which is mounted on a threaded valve stem, a pinion on said valve stem, a sprocket wheel loosely mounted on said tube construction, a gear on said sprocket wheel for driving said pinion, a pawl connected with said sprocket wheel adapted to engage the blow tube construction and rotate it in either direction of rotation of the sprocket wheel, a cam adapted to disengage said pawl at a certain period of the rotary movement of the sprocket wheel, and means for mounting said cam so it will be adjustable in a line concentric to the axis of the sprocket wheel.

8. A soot blower including a rotatable blow tube construction, a stationary plate surrounding the same and in which it is mounted, said plate having an undercut groove in its outer face concentric with the axis of the blow tube, a pipe for supplying steam to said blow tube construction, a valve for controlling said steam supply, a sprocket

wheel loosely mounted on the blow tube construction, means whereby the sprocket wheel when turned in one direction will open the valve and when turned in the opposite direction will close the valve, a pawl carried by the sprocket wheel adapted to engage the soot blower construction and rotate the same, and a spring-held arm adjustably mounted in the said undercut slot in said plate and curved concentric with the axis of the blow tube and having a cam on its free end in position to engage the pawl for disengaging it from the blow tube construction, whereby the latter will be stationary during a part of the cycle of operation of the device.

9. A soot blower including a rotatable blow tube construction, a stationary plate surrounding the same and in which it is mounted, said plate having an undercut groove in its outer face concentric with the axis of the blow tube, a pipe for supplying steam to said blow tube construction, a valve for controlling said steam supply, a sprocket wheel loosely mounted on the blow tube construction, means whereby the sprocket wheel when turned in one direction will open the valve and when turned in the opposite direction will close the valve, a pawl carried by the sprocket wheel adapted to engage the soot blower construction and rotate the same, and a spring-held arm adjustably mounted in the said undercut slot in said plate and curved concentric with the axis of the blow tube and having a cam on its free end in position to engage the pawl for disengaging it from the blow tube construction, whereby the latter will be stationary during a part of the cycle of operation of the device, and said cam also being shaped so as to permit engagement of the pawl with the blow tube construction on the reverse movement of the sprocket wheel.

10. In a soot blower, the combination of a blower arm, means for oscillating the same, means for supplying steam to said arm, a horizontally disposed valve for controlling said supply means, said valve having a rotary stem extending in the same direction as the blower arm, a gear on said stem and a gear on said arm engageable with the first gear to transmit motion to the valve stem from the arm.

In witness whereof, we have hereunto affixed our signatures.
